UNITED STATES PATENT OFFICE

153,096

DESIGN FOR A VANITY CASE

Claude Arpels, New York, N. Y.

Application September 5, 1946, Serial No. 133,083

Term of patent 3½ years

(Cl. D86—10)

To all whom it may concern:

Be it known that I, Claude Arpels, a citizen of the United States of America, residing in New York city, county of New York, and State of New York, have invented a new, original, and ornamental Design for a Vanity Case, of which the following is a specification, reference being had to the accompanying drawing, forming a part thereof.

Fig. 1 is a rear perspective view of a vanity case.

Fig. 2 is a front perspective view, showing my new design.

The end of the vanity case not shown is substantially like that disclosed.

I claim:

The ornamental design for a vanity case, substantially as shown and described.

CLAUDE ARPELS.
